Des. 184,372
Patented Feb. 3, 1959

184,372

WEATHER VANE

John J. Richards, Wauwatosa, and Merlin E. Kottke,
Milwaukee, Wis.

Application June 30, 1958, Serial No. 51,605

Term of patent 14 years

(Cl. D52—1)

The drawing figure is a perspective of a weather vane, showing our new design.

We claim:

The ornamental design for a weather vane, as shown.
